UNITED STATES PATENT OFFICE

JAMES A. KINNEY, OF LEBANON, PENNSYLVANIA, ASSIGNOR TO BETHLEHEM STEEL COMPANY

NUT-FORGING MACHINE

Application filed March 31, 1926. Serial No. 98,690.

My invention relates to a bar feeding mechanism and particularly to a mechanism for feeding the stock bar to the hot nut forging machine.

Heretofore, it has been customary for the operator to feed the stock bar to a nut forging machine by hand against a stop in juxtaposition to the shearing plunger which successively shears off a separate nut blank from the end of the bar and pushes the same into the die which shapes it to the configuration desired in the finished nut. Mechanisms have been suggested for feeding the stock bar automatically into the machine, however, such mechanisms have not been successful owing to the end of the bar being distorted by the plunger upon its return stroke after shearing the nut blank, due to the pressure between the end of the bar and the side of the punch.

The object of my invention is to provide a mechanism for intermittently feeding the stock bar to a nut forging machine and means are provided whereby the bar is slightly retracted so that it is out of contact with the punch during the return stroke of the latter after it has sheared off the nut blank.

Another object of my invention is to provide means for mechanically removing the scale or cleaning certain surfaces of the stock bar as it is being fed to a nut forging machine.

The invention comprises generally a unit constituting a feed mechanism which is easily attached to a standard nut forging machine and includes a pair of feed rolls operated by a ratchet arrangement which is actuated by the main cam shaft of the forging machine and in timed relation to the operation of the forging tools of said machine, whereby the stock bar is advanced and retracted automatically in accordance with the relative position of said tools. The feed rolls are provided with a peripheral flange having the inside surface thereof roughened to engage the surface of the stock bar with an abrasive action, while feeding, to remove the scale or other extraneous matter from the surfaces of the bar which do not come in contact with the

dies in the subsequent forging operation of the nut blank.

Referring now to the accompanying drawings, in which

Fig. 1 is a longitudinal sectional view of the forging machine,

Fig. 2 is a plan view of the bar feeding mechanism, mounted on the frame of a nut forging machine;

Fig. 3 is an end elevation of the mechanism shown in Fig. 2;

Fig. 4 is a sectional view taken on line IV—IV of Fig. 2, and illustrating the feed ratchet arrangement;

Fig. 5 is a side elevation of the mechanism shown in Fig. 2;

Fig. 6 is an end elevation of an alternative ratchet arrangement;

Fig. 7 is a detail view of the ratchet mechanism shown in Fig. 2;

Fig. 8 is a sectional view taken on line VIII—VIII of Fig. 7;

Fig. 9 is a side elevation of the retracting pawl;

Fig. 10 is a side elevation of the cam which operates the kicker; and,

Figs. 11 and 12 are detail views of the alternative ratchet mechanism shown in Fig. 6.

In the drawings, the machine comprises a frame 10 provided with suitable bearings for the crank shaft 11 and the cam shaft 12. The shafts 11 and 12 are rotated by means of gear wheels 13 and 14, respectively, which are keyed to said shafts and are driven through

gearing from the common power shaft 15. A slide block 16 is journaled on the crank shaft 11 and is slidably mounted in a guideway formed in the cross head 17 to cause a reciprocatory motion to the latter when the crank shaft is rotated. The cross head carries the shearing plunger 18 which advances part way through the opening 19 formed in the die block 20. The crowning plunger 21 is mounted on the slide 22 which reciprocates in suitable horizontal guides fixed to the frame 10.

Slidably mounted in the slide 22 is a punch block 23 to which is fixedly mounted the punch 24. The slide 22 and the punch block 23 are constrained to their rearward movement by a pair of stops 25 and 26 which are fixed to the frame 10. The punch 24 is urged forward by a spring 27 which is anchored to the rear of the punch block 23 and to the frame 10. The rear end of the punch block 23 is provided with a shoulder 28 which is urged rearward by a spring 29 which is anchored to the rear of the punch block 23 and to the frame 10. The rear end of the punch block 23 is provided with a shoulder 28 which is urged rearward by a spring 29 which is anchored to the rear of the punch block 23 and to the frame 10.

position by means of leaf springs 25 and are moved forwardly towards the die block 20 by the cams 26 and 27, fixedly mounted on the cam shaft 12 which engages the depending portions 28 and 29 of the slide and punch block, respectively. The stock bar is advanced between the guides 30 against a stop (not shown) to a position before the die opening, the tools aforementioned operate in 10 timed relation to forge a nut in a manner well known in the art. The tools operate in the following sequence: The shearing plunger 18 advancing shears off a nut blank from the end of the stock bar which is pressed into the die opening against the crowning plunger 21. The timing of the operation is so arranged that the blank is squeezed between plungers 18 and 21 so that the blank is crowned and pressed into the correct configuration against the surfaces of the die block. While the blank is thus held it is pierced by the advancing punch 24. After the piercing is effected, the plunger 18 retracts and the plunger 21, continuing to advance, ejects the 25 blank from the die. The plunger 18 is bored centrally to receive the slug punched from the blank, and the slug is ejected from the plunger by means of the ejector 31 mounted in said plunger, which engages the stop 32 30 when the plunger approaches its rearward position.

I will now describe the mechanism for feeding the stock bar to the forging tools. A standard 33 is bolted to the side of the frame 35 10 and has journaled thereto a pair of shafts 34 and 35 which carry the pinch rollers 36 and 37, respectively. The bottom shaft 34 is mounted in ordinary cap bearings attached to the standard 33, however, in order that the 40 pinch rolls may be adjusted to receive various sized bars and further so that the grip of the pinch rolls on the bar may be quickly released, I provide different type of mounting for the top shaft 35. One end of the 45 latter shaft is mounted in a journal block 38 and the other end of said shaft is mounted in the bearing block 39. The journal 38 is hinged to the standard 33 by means of trunnions 40 and the bearing block 39 is slidingly 50 mounted in the yoke 41 which extends vertically from the standard. A coil spring 42 is interposed between the bridge piece 43 of the yoke 41 and the top of the bearing block 40, to yieldingly urge the pinch rolls towards 55 each other. The initial compression of the spring 42 is adjusted by means of the set screw 44 threaded to the bridge piece 43, the set screw 44 being provided with a collar abutment 45 which bears against the end of 60 said spring. Flanges 46 and 47 are removably fastened by suitable fastening means, such as bolts 48, to the pinch rolls 36 and 37, respectively, to guide the stock bar through the rolls and the inside surfaces of the flanges 65 are serrated or roughened, as at 49, see Fig.

5, to cause an abrasive action on the side faces of the bar and clean them as the bar is fed through the rolls. The shafts 34 and 35 are spaced apart and the initial compression on the coil spring 42 is such that the smallest 70 bar fed to the machine will enter the space between the pinch rolls and spread the latter apart, the journal 38 rotating about the trunnions 40 allows the shaft 35 to be raised vertically constrained by the coil spring 42 75 and sufficient traction is provided by the compression of said spring to feed the bar when the shaft 34 is rotated in the manner herein-after described. The initial compression on the coil spring 42 is adjusted by means of the 80 set screw 44 to accommodate various sizes of the bars which may be fed to the forging machine so that a bar may easily enter the pinch rolls and be gripped with sufficient force by the latter to provide traction between the contiguous surfaces. The pinch roll 36 is fixed axially on the shaft 34, whereas the pinch roll 37 is slidingly mounted on the shaft 35 and is constrained against the adjustable collar 50, threaded to the end of the 90 shaft, by means of the coil spring 51 surrounding the shaft and interposed between the bearing block and the pinch roll 37, so that the flange 46 may be adjusted in its axial relation to the flange 47, by means of the collar 50 to accommodate various thicknesses of 95 the bars which may be fed to the machine.

A horizontal shaft 52 is journaled in the standard 33 and is provided with a lifting cam 53 which, when the shaft 52 is rotated 100 by means of the handle 54 keyed thereto, engages the under side of the bearing block 39 and lifts the shaft 35 vertically against the spring 42, thus spreading the pinch rolls apart so that the bar may be easily withdrawn from the machine when desired. The bearing surfaces of the lifting cam 53 are so shaped that when the cam is in its vertical or elevated position, it is retained in that position by its contact with the bearing block 110 39 and the rolls are maintained apart until the shaft 52 is rotated to lower the cam back to its original position. The pinch rolls are rotated intermittently and in timed relation to the nut forging tools of the machine by 115 means of the cam 55, fixed at the extending end of the cam shaft 12, operating a ratchet mechanism which is described as follows: Keyed to the shaft 34 are a pair of ratchet wheels 56 and 57 having buttress teeth formed at their periphery and disposed in opposite relation so that the pawls when alternately operated engage with their respective ratchet wheels and the shaft 34 is rotated intermittently and alternately in opposite directions. 120 The pawl 58 engages the teeth on the ratchet wheel 56 to rotate the pinch rolls in the direction to feed the bar to the forging machine and after the blank is sheared from the end of the bar, the pawl 59 by its operative en- 125 130

gagement with the ratchet wheel 57 rotates the pinch rolls so as to slightly retract or back the bar out of contact with the shearing plunger 18. The pawl 58 is pivotally mounted at the upper end of the slide 60 and is constrained in contact with the periphery of the ratchet wheel 56 by the coil spring 61 anchored to the post 62 which is fixed to the standard 33. The slide 60 is mounted in suitable vertical guides attached to the frame 10 and is normally held in its upper position by a coil spring 63, the latter surrounds the threaded rod 64, depending from the slide, and is interposed between a fixed bracket 65 and an adjustable collar 66 threaded on the rod. The rod 64 extends through an aperture formed in the bracket 65 and has threaded thereto a nut 66' which engages the bracket 65 to limit the upward movement of the slide 60 and cooperates with the collar 66 to adjust the initial compression of the coil spring.

A roller 67 is mounted on a pin which extends laterally from the slide 60 and cooperates with the cam 55 to push the slide downwardly against the force of the coil spring 63. When the slide is pushed downwardly the pawl 58 engages the buttress face of a tooth at the periphery of the ratchet wheel 56 and rotates the shaft 34, which causes the shaft 35 to rotate, through the medium of the meshed gears 68 and 69, thus feeding the bar gripped between the pinch rolls to the machine. The slide 60 is moved upwardly by the force of the spring 63 and during this movement the pawl 58 trails the teeth formed on the periphery of the ratchet wheel and does not operate to rotate the latter. Normally the roller 67 engages the periphery of the cam 55 during its complete rotation and the slide 60 is actuated thereby through a distance which corresponds to the throw of the cam. It will be seen that by adjusting the nut 66' the slide 60 may be held in its uppermost position so that the roller 67 is not in contact with the cam 55 during a certain portion of the angular movement of the latter and during such angular movement does not actuate the slide, thus the stroke of the latter is shortened. In this manner the feed of the bar in the pinch rolls can be regulated.

A latch 70 is keyed to the rod 71 which is journaled to the frame 10 and is adapted to be swung in front of the abutment shoulder 72 formed on the slide 60 when the latter is in its lowermost position to hold the slide in the latter position and the roller out of engagement with the cam 55, so that the cam may continue to rotate without actuating the pinch rolls to feed the bar to the machine. The latch 70 is normally constrained out of the path of the shoulder 72 by counterbalancing effect of the handle 74 fixed to the rod 71. The handle 74 is placed in a convenient

position to the operator of the machine so that it may be moved to cause the latch 70 to engage the shoulder 72, whereby the automatic feed may be instantly discontinued in event of mishap to the machine. The pawl 59 is pivoted to the bracket 75 which is adjustably mounted on the slide 76. The pawl 59 is held yieldingly in contact with the periphery of the ratchet wheel 57 by means of the coil spring 77 which is attached to the pawl and anchored at its other end to the bracket 75. It will be seen in Figs. 2 and 3 that the slide 76 is mounted in suitable vertical guides attached to the frame 10 and has a roller 78 mounted on a suitable bearing at its upper end which cooperates with the cam 55 to actuate the slide. The roller 78 is held in contact with the periphery of the cam 55 by gravity. The operation of the cam is timed so that the slide 76 is forced upwardly and the pawl 59 engages the buttress face of a tooth formed at the periphery of the ratchet wheel 57 to effect the rotation of the pinch rolls in the direction to slightly retract the stock bar out of contact with the shearing plunger after the latter has sheared a nut blank from the end of the bar; in this manner distortion of the end of the bar is prevented which would otherwise occur if the bar was allowed to drag on the plunger during its return stroke. In order that the effective stroke of the slide 76 can be adjusted within certain limits, the bracket 75 is clamped to the slide 76 by bolts 79 which pass through elongated apertures formed in the bracket. A set screw 80 is threaded in a lug extending from the side of the slide 76 and engages the lower end of the bracket 75. By loosening the bolts 79 and manipulating the set screw 80 the position of the pawl 59 may be adjusted relatively to the ratchet wheel 57. This provides a means whereby the amount the stock bar is retracted may be controlled without changing the elements of the feeding mechanisms. When the slide 76 is moving downwardly the pawl 59 trails over the back of the teeth formed at the periphery of the ratchet wheel and does not operate to rotate the pinch rolls.

The feeding mechanism described in the foregoing part of the specification is particularly suitable for bars of a size which may be easily removed by hand from the machine after the pinch rolls have been spread apart by the lifting cam 53. However, bars of comparatively large size are difficult to handle and it is preferable to provide power means to feed the bar out of the pinch rolls. The slide 76, already described above, has a comparatively small stroke only sufficient to rotate the pinch rolls to retract the bar end out of contact with the shearing plunger and it would be tedious and inefficient to use this arrangement for removing bars from the machine.

Referring to Figs. 6, 11, and 12, there is illustrated an alternate feeding mechanism which is particularly suitable for feeding a stock bar of large size to the nut forging machine.

In the latter feeding arrangement, there is incorporated a reversible pawl 58', see Fig. 6, which is adapted to be placed in operative engagement with the ratchet wheels 56 to 10 feed the bar to the forging machine or may be reversed to operatively engage the teeth of the ratchet wheel 57 to feed the bar out of the machine. In this manner the bar is removed from the machine faster than it is 15 fed to the machine for the reason that when the mechanism is adjusted to withdraw the bar the feed of the pawl 58' is augmented by the feed of the backing pawl 59'. The reversible pawl 58' is rotatably mounted in 20 suitable bearings on the arm 81 which extends upwardly from the boss 82 and outwardly over the ratchet wheels 56 and 57. The boss 82 is rotatably mounted on the shaft 34 and has a radially extending lug 83 which 25 is connected to the slide 60' by means of a link 84. The slide 60' is mounted in suitable vertical guides attached to the standard 33' and has at its upper end, a laterally extending pin carrying a roller 67' which engages 30 a contained or double faced cam path formed in the face of cam 55' keyed to the extending end of the cam shaft 12. The roller 67' cooperates with the cam 55' to reciprocate the slide 60' in timed relation with the operation 35 of the nut forming tools. The periphery of the cam 55' engages the roller 78' and cooperates therewith to actuate the backing mechanism which is similar in operation to the backing mechanism heretofore described. 40 The reversible pawl 58' comprises a shaft 85 journaled in the arm 81 and having, keyed thereto, a dog portion 86 which is positioned over the ratchet wheel 56 and has a second dog portion 87 keyed thereto which extends 45 in the opposite direction over ratchet wheel 57.

The shaft 85 extends beyond its bearings and has keyed to it a horizontally disposed crank arm 88 which, owing to its counter- 50 balancing effect, normally urges the dog 86 into engagement with the periphery of the ratchet wheel 56. Extending vertically from the arm 88 is a rod 89 having an eye which is attached to a spring 90. Fastened 55 to the latter is a cable 91 which is carried by suitable pulleys to a convenient position so that the operator may, by means of the cable, raise the arm 88 to place the pawl 58' in a neutral position so that neither of the dog 60 portions 86 and 87 are in contact with their respective ratchet wheels or by further movement of the cable place the dog portion 87 in engagement with the periphery of ratchet wheel 57. In this latter position the dog 65 portion 87 yieldingly engages its associated

ratchet wheel and when the slide 60' reciprocates, the pinch rolls are operated to feed the stock bar out of the machine. The cable may be held by the operator in its various positions or attached to a suitable bracket within 70 convenient reach of the operator. When the dog portion 87 is set in position to engage the periphery of its associated ratchet wheel and during the downward movement of the slide 60', the extension spring 90 yields and 75 allows the pawl to trail the teeth of the ratchet wheel without operating the pinch rolls.

In operation, the stock bar is fed from a furnace (not shown), which is preferably placed in alignment with the forging machine, to the fixed guide 92 and is guided between the pinch rolls which are rotated by 80 the ratchet mechanism described above to mechanically feed the bar to the forging tools, or the pinch rolls may be spread apart

by the means described above and after the bar is pushed against the stop to a position in front of the die opening the rolls are allowed to again engage the bar. When the bar is thus positioned the shearing plunger 18 advances and shears off the nut blank and 85 presses the latter into the die opening 19 which may be shaped to form a nut of any desired configuration, such as square, hexagon, etc. In the meantime the crowning plunger 21 advances and backs up the nut blank which is momentarily squeezed between the plungers, thereby crowning the nut and 90 pressing the metal radially against the surfaces of the die opening. While the blank is thus held the punch 24 advances and pierces the blank, the slug which is removed being received in the hollow shearing plunger. At 95 this point the latter recedes and the crowning plunger 21 continues to advance, though somewhat slower than the movement of the shearing plunger and at the same time the punch 24 recedes and the blank is stripped therefrom and is ejected from the die by the advancing crowning plunger. As the shearing plunger reaches its rearward position, 100 the ejector contacts with the stop 32 and ejects the slug, aforementioned, from said plunger. The nut blank can be kicked off the end of the crowning plunger when it 105 emerges from the die by a suitable kicker, such for example, as the rod 93 depended from the rocking lever 94 which is actuated by the cam 95 mounted on the cam shaft 12. Just before the shearing plunger commences 110 to recede, as described above, the cam 55 operates to actuate the slide 76 so that the pawl 59 engages a tooth on its associated ratchet wheel and slightly rotates the pinch rolls 115 whereby the end of the stock bar is backed out of contact with the shearing plunger. When the nut blank has been ejected, the cam 55 is timed to operate the slide 60 so that the pawl 58 engages a tooth on its associated ratchet wheel to rotate the pinch rolls and 120

125

130

feed the stock bar to a position before the die opening for the formation of a second nut blank. The operation continues automatically, nut blanks being successively formed until the stock bar is consumed. When the remaining end of the stock bar is of insufficient length to be fed by the pinch rolls, it is retained in position by the fixed guides 96 and the bar is pushed into position by the contiguous end of the next stock bar fed through the pinch rolls.

At the outlet side of the fixed guide 96 I provide a guide 97 which yieldingly holds the stock bar so that a comparatively short length of bar is held in correct position before the die opening so that a maximum number of nut blanks may be obtained from the bar without waste. The supporting surfaces of the guide 97 are curved, as at 98, so that the waste end of the bar will easily fall out of the machine if there is not sufficient material left to form a complete nut. The upper block 99 of the guide 97 is depended from an arm 100 which is pivoted to a bracket adjustably mounted on the frame 12. The opening of the guide 97 is adjusted by means of the set screw 101 threaded to the arm 100 and bears against a fixed plate 102. The upper block 99 is constrained in its lower adjusted position by means of the extension spring 103 which is connected to the extending end of the arm 100 and suitably anchored at its other end to the frame 10. Normally the distance between the horizontal bar engaging surfaces of the guide 97 is somewhat less than the width of the bar so that as the bar enters the guide the upper block is forced upward against the force of the spring 103 and yieldingly holds the bar as it passes through the guide.

As the bar passes through the pinch rolls, the serrated or roughened faces of the flanges 46 and 47, by their abrasive action, automatically cleans the faces of the bar and removes the scale or other extraneous matter therefrom. The edges of the bar are freed from scale by the shearing action of the forging die so it will be seen that the surfaces of the nut blank are entirely freed from scale and this results in a better type of product than those produced in the usual type of hot nut forging machines.

From the foregoing description, it will be seen that I have devised a feeding mechanism which is simple in construction and easily attached to any well known nut forging machine, and cooperates with a machine to produce nut blanks from a stock bar with very little attention on the part of the operator. Furthermore, by providing an automatic feeding mechanism, I am able to place the forging machine in contiguity with a heating furnace so that the bar may be fed directly from the furnace to the machine, thus the nut blanks are formed continuously with-

out returning the bar to the furnace to be re-heated as is generally found necessary to do when feeding the bars by hand.

While I have shown my invention in two forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

Having thus described the invention, what I claim as new and desire to secure by Letters Patent is:

1. In a nut forging machine, the combination of a die block, reciprocating tools, means to actuate said tools and a mechanism for feeding a stock bar, said mechanism comprising a pair of rolls, means to rotate said rolls intermittently in one direction and means to rotate said rolls intermittently through a lesser angular movement in the reverse direction.

2. In a nut forging machine, the combination of a die block, reciprocating tools, a cam shaft to actuate said tools, and a mechanism for feeding a stock bar, said mechanism comprising a pair of shafts, feed rolls mounted on said shafts, a ratchet wheel keyed to one of said shafts, a reciprocating slide, a pawl mounted on said slide and adapted to engage said ratchet wheel, whereby a particular movement of said slide causes the feed rolls to feed the stock bar to the tools, a reverse ratchet wheel also mounted on the last mentioned shaft, a second reciprocating slide having a pawl mounted thereon and adapted to engage the reverse ratchet wheel, whereby a particular movement of said second slide causes the feed rolls to retract the stock bar from the tools, and a cam fixed to said cam shaft to actuate said slides.

3. In a nut forging machine, the combination of a die block, reciprocating tools, means to actuate said tools, and a mechanism for feeding a stock bar, said mechanism comprising a pair of shafts, feed rolls mounted on said shafts, means to yieldingly constrain said rolls towards each other, a pair of ratchet wheels fixed to one of said shafts and disposed in opposite operative relation to each other, means to intermittently engage said ratchet wheels alternately to cause the rotation of said feed rolls, to alternately feed the stock bar to the tools and to retract it, and means to actuate the last mentioned means in timed relation to the operation of said tools.

4. In a nut forging machine, the combination of a die block, reciprocating tools, means to actuate said tools, and a mechanism for feeding a stock bar, said mechanism comprising a pair of shafts, a roll mounted on each of said shafts, a ratchet wheel fixed to one of said shafts, a reciprocating slide, a pawl member

mounted on said slide and adapted to engage said ratchet wheel, a rotatable cam to actuate said slide, and means controlled by the operator to hold the slide out of engagement with said cam, thereby rendering the latter inoperative.

5. In a nut forging machine the combination of a die block, reciprocating tools, means to actuate said tools, a pair of rolls adapted
10 to transfer a stock bar, means to intermittently rotate said rolls to advance the bar towards said tools, means to intermittently rotate said rolls to back the bar in a reverse direction, and means to actuate said rotating means in
15 timed relation to the operation of said tools.

In testimony whereof I hereunto affix my
signature this 27 day of March, 1926.

JAMES A. KINNEY.
